[57] CLAIM

The ornamental design for a router edge guide, as shown and described.

DESCRIPTION

FIG. 1 is a front top left perspective view of a router edge guide having a mounting bar and mounting rods of a first configuration;

FIG. 2 is a front elevational view of the router edge guide shown in FIG. 1;

FIG. 3 is a rear elevational view of the router edge guide shown in FIG. 1;

FIG. 4 is a top plan view of the router edge guide shown in FIG. 1;

FIG. 5 is a bottom plan view of the router edge guide shown in FIG. 1;

FIG. 6 is a left side elevational view of the router edge guide shown in FIG. 1;

FIG. 7 is a right side elevational view of the router edge guide shown in FIG. 1;

FIG. 8 is a front top left perspective view of a router edge guide having a mounting bar and mounting rods of a second configuration;

FIG. 9 is a front elevational view of the router edge guide shown in FIG. 8;

FIG. 10 is a rear elevational view of the router edge guide shown in FIG. 8;

FIG. 11 is a top plan view of the router edge guide shown in FIG. 8;

FIG. 12 is a bottom plan view of the router edge guide shown in FIG. 8;

FIG. 13 is a left side elevational view of the router edge guide shown in FIG. 8; and,

FIG. 14 is a right side elevational view of the router edge guide shown in FIG. 8.
